UNITED STATES PATENT OFFICE.

WARREN WARD LEWARD, OF OTSEGO, MICHIGAN.

CONVERTIBLE CHAIR.

No. 907,253.

Specification of Letters Patent.

Patented Dec. 22, 1908.

Application filed October 17, 1907. Serial No. 397,807.

To all whom it may concern:

Be it known that I, WARREN WARD LEWARD, a citizen of the United States, residing at the village of Otsego, county of Allegan, 5 State of Michigan, have invented certain new and useful Improvements in Convertible Chairs, of which the following is a specification.

This invention relates to improvements in 10 convertible chairs.

The main objects of this invention are: first, to provide an improved convertible chair which may be readily adjusted or converted into a high chair or a rocking chair, as 15 desired; and second, to provide an improved convertible chair having an adjustable foot rest which is automatically extended when the chair is adjusted as a high chair and collapsed when the same is adjusted as a rocking 20 chair.

Further objects, and objects relating to details of construction, will definitely appear from the detailed description to follow.

I accomplish the objects of my invention 25 by the devices and means described in the following specification. The invention is clearly defined and pointed out in the claims.

A structure embodying the features of my invention is clearly illustrated in the accompanying drawing, forming a part of this 30 specification, in which:

Figure 1 is a side elevation of a structure embodying the features of my invention adjusted as a rocking chair; Fig. 2 is a detail 35 front elevation thereof; Fig. 3 is a detail vertical section taken on a line corresponding to line 3—3 of Fig. 2; Fig. 4 is an elevation partially in vertical section of my improved chair adjusted as a high chair; Fig. 5 is an 40 enlarged detail section taken on a line corresponding to line 5—5 of Fig. 1; and Fig. 6 is an enlarged detail section taken on a line corresponding to line 6—6 of Fig. 4, showing the latch or locking mechanism for maintaining 45 the parts when adjusted as a high chair.

In the drawings the sectional views are taken looking in the direction of the little arrows at the ends of the section lines, and similar reference characters refer to similar 50 parts throughout the several views.

Referring to the drawing, the seat is of the usual or any desired form and is preferably provided with a back as 2 and with arms 3 similar to the ordinary child's high chair or 55 rocking chair. The short front legs 4 are

rigidly secured to the seat. The short rear legs 5 are pivotally secured to the seat, the seat being preferably provided with a cross piece 6 to which the leg pivots 7 are secured. The rockers are each formed of two members, 8 and 9, the same being similarly shaped and arranged side by side so that the structure has the appearance of having single rockers when adjusted as a rocking chair. These rocker members are pivotally secured to each other by the pivot rod 10 which preferably extends across the chair serving to brace the same. The outer rocker members 8 are preferably longer than the inner members 9, the same extending rearwardly beyond the same, 70 as clearly appears from the drawing, the outer members being connected by a cross rod 11 arranged at the rear end of the inner rocker members. The forward ends of the outer rocker members are connected by pivots as 12 to the lower ends of the front legs. The rear ends of the inner rocker members 9 are connected as by the pivot rod 13 to the lower ends of the rear legs 5, as clearly appears from the drawing, so that when the chair is adjusted as a high chair the ends of the rocker members are swung up to form extensions for legs, as clearly appears in Fig. 4.

The foot rest 14 is mounted by the pivots 15 on the front legs so as to fold inwardly 85 between the same when collapsed and outwardly into operative position when extended, see Figs. 3 and 4. The foot rest is connected by the link 16 to the rear legs 5 the link being pivotally connected to the 90 foot rest and to the legs, so that when the legs are swung inwardly, as is the case when the chair is adjusted as a high chair, the foot rest is swung out into its extended position, and when the legs are swung rearwardly, as 95 is the case when the chair is adjusted as a rocking chair, (see Fig. 3), the foot rest is thrown inwardly by the link.

The parts are locked in their erected position by means of the latch 17 which is preferably hung on the under side of the seat so as to engage over a cross piece 18 connecting the links 16 when the parts are adjusted as a high chair. This effectively prevents their collapsing by preventing the raising of the 100 links 16 until the latch is disengaged, the latch thus coacting with the links to form a lock for the parts. The latch 17 is preferably provided with a shoulder or stop 22 adapted to serve as a support for the foot 110

rest in its inner position. This limits the downward movement of the foot rest so there is no liability of the parts becoming locked, owing to the pivot connections for the links 16 to the foot rest swinging down past the center of the pivot connections for the link and foot rest to the legs. The latch is preferably operated by a push rod 19 which is preferably arranged through the cross piece 6 on the under side of the seat and is provided with a finger piece or button 20 on its rear end adapted to be manipulated from the rear of the chair. When it is desired to collapse the chair or adjust it as a rocking chair, this push rod is pushed inwardly, thereby releasing the latch 17 and allowing the parts to close down into the position shown in Fig. 3. This automatically turns the foot rest inward, as is illustrated in that figure.

When it is desired to erect the chair, it is only necessary to lift upwardly on the seat, the operator ordinarily stepping on the cross piece 11 for the outer rocker members when the catch 17 will automatically engage the cross piece 18, locking it in position, a spring 21 being provided for applying tension to the catch.

The hinge members 23 for securing the front legs to the rocker members 8 are preferably formed integral with the braces 24, thereby reducing the number of parts and forming a very rigid construction.

The front legs are adapted to rest upon the rocker members 9 when the chair is adjusted as a rocking chair, thereby keeping the rocker members in alignment and preventing movement of the parts on each other.

The structure is very simple and at the same time strong and rigid and may be, and is obviously, quickly converted from a high chair to a rocking chair, or vice versa.

I have illustrated and described my improved convertible chair in detail in the form preferred by me on account of structural simplicity. I am, however, aware that it is capable of considerable variation in structural details without departing from my invention and I desire to be understood as claiming the same specifically, as illustrated, as well as broadly.

Having thus described my invention, what I claim as new and desire to secure by Letters Patent is:

1. In a convertible chair, the combination of a seat; rigid front legs therefor; rockers, each formed of two pieces or members arranged side by side and pivotally connected to each other, a member of each rocker being pivoted at its forward end to the lower end of one of the front legs; rear legs pivotally connected to said seat and to the other rocker members so that the rear ends of said rocker members may be swung up when the chair is

adjusted as a high chair to form extensions for the said rear legs; a foot rest pivotally mounted on the said front legs; a link pivoted thereto and to the said rear legs whereby the said foot rest is extended when the chair is adjusted as a high-chair and collapsed when the same is adjusted as a rocking chair; a catch adapted to engage said link when the chair is erected as a high chair, whereby the said parts are locked in position; a push rod for disengaging said catch; and a spring on said push rod whereby said catch is automatically engaged.

2. In a convertible chair, the combination of a seat; rigid front legs therefor; rockers, each formed of two pieces or members arranged side by side and pivotally connected to each other, a member of each rocker being pivoted at its forward end to the lower end of one of the front legs; rear legs pivotally connected to said seat and to the other rocker members so that the rear ends of said rocker members may be swung up when the chair is adjusted as a high chair to form extensions for the said rear legs; a foot rest pivotally mounted on the said front legs; a link pivoted thereto and to the said rear legs whereby the said foot rest is extended when the chair is adjusted as a high chair and collapsed when the same is adjusted as a rocking chair; and a catch adapted to engage said link when the chair is erected as a high chair, whereby the said parts are locked in position.

3. In a convertible chair, the combination of a seat; rigid front legs therefor; rockers, each formed of two pieces or members arranged side by side and pivotally connected to each other, a member of each rocker being pivoted at its forward end to the lower end of one of the front legs; rear legs pivotally connected to said seat and to the other rocker members so that the rear ends of said rocker members may be swung up when the chair is adjusted as a high chair to form extensions for the said rear legs; a foot rest pivotally mounted on the said front legs; and a link pivoted thereto and to the said rear legs whereby the said foot rest is extended when the chair is adjusted as a high chair and collapsed when the same is adjusted as a rocking chair.

4. In a convertible chair, the combination of a seat; rigid front legs therefor; rockers, each formed of two pieces or members arranged side by side and pivotally connected to each other, a member of each rocker being pivoted at its forward end to the lower end of one of the front legs; rear legs pivotally connected to said seat and to the other rocker members so that the rear ends of said rocker members may be swung up when the chair is adjusted as a high chair to form extensions for the said rear legs; a foot rest pivotally mounted on the said front legs and connections therefor to the said rear legs whereby the

said foot rest is extended when the chair is adjusted as a high chair and collapsed when the same is adjusted as a rocking chair.

5. In a convertible chair, the combination of a seat; rigid front legs therefor; rockers, each formed of two pieces or members arranged side by side and pivotally connected to each other, a member of each rocker being pivoted at its forward end to the lower end 10 of one of the front legs; rear legs pivotally connected to said seat and to the other rocker members so that the rear ends of said rocker members may be swung up when the chair is adjusted as a high chair to form 15 extensions for the said rear legs; an adjustably mounted foot rest; and connections therefor to the said rear legs whereby the said foot rest is extended when the chair is adjusted as a high chair and collapsed when 20 the same is adjusted as a rocking chair.

6. In a convertible chair, the combination of a seat; legs therefor the rear pair of legs being pivoted; rocker members adapted to serve as extensions for said legs when said 25 chair is adjusted as a high chair and as rockers when said chair is adjusted as a rocking chair; an adjustably mounted foot rest and connections therefor to the said pivoted rear legs, whereby said foot rest is 30 automatically extended when the chair is adjusted as a high chair and collapsed when the same is adjusted as a rocking chair.

7. In a convertible chair, the combination of a seat; rigid front legs therefor; rockers, 35 each formed of two pieces or members ar-

ranged side by side and pivotally connected to each other; braces for said front legs secured at one end to said seat and to said legs, said braces being extended into hinge members, to which a member of each of said rockers is 40 pivoted at its forward end; rear legs pivotally connected to said seat and to the other rocker members so that the rear ends may be swung up when the chair is adjusted as a 45 high chair to form extensions for the said rear legs; and said front legs being arranged to rest on the rocker members pivoted to the rear legs when the chair is adjusted as a rocking chair.

8. In a convertible chair, the combination of a seat; rigid front legs therefor; rockers, each formed of two pieces or members arranged side by side and pivotally connected to each other; braces for said front legs secured at one end to said seat and to 50 said legs, said braces being extended into hinge members, to which a member of each of said rockers is pivoted at its forward end; and rear legs pivotally connected to said seat and to the other rocker members so 55 that the rear ends may be swung up when the chair is arranged as a high chair to form extensions for the said rear legs.

In witness whereof, I have hereunto set my hand and seal in the presence of two 60 witnesses.
